UNITED STATES PATENT OFFICE.

CLETUS N. ALLERDING, OF MANSFIELD, OHIO, ASSIGNOR TO THE OHIO BRASS COMPANY, OF MANSFIELD, OHIO, A CORPORATION OF NEW JERSEY.

TROLLEY-LINE CLAMP.

1,049,189.

Specification of Letters Patent.

Patented Dec. 31, 1912.

Application filed December 7, 1910. Serial No. 596,015.

To all whom it may concern:

Be it known that I, CLETUS N. ALLERDING, a citizen of the United States, residing at Mansfield, in the county of Richland and 5 State of Ohio, have invented certain new and useful Improvements in Trolley-Line Clamps, of which the following is a specification.

This invention relates to trolley line 10 clamps and has for its primary object to provide an improved construction, combination and arrangement of parts in a trolley line clamping device of positive action and adapted to be readily inserted into and 15 removed from operative position.

Another object is to provide an improved device of this character having means whereby a strong clamping action may be secured with a small expenditure of energy.

20 Another object is to provide an improved suspension for the trolley line clamp which shall coöperate therewith to support the same in engagement with the trolley line while the clamp is being tightened on said 25 trolley line.

Another object is to provide improved means for locking the clamping members together to prevent dis-association of the same.

30 Another object is to provide an improved trolley clamp of this character having means for detachably and adjustably connecting the clamp to its support or hanger and also having swivel jaws whereby a perfect alinement with the trolley wire may be obtained when the parts are secured together.

Other and further objects will appear in 40 the specification and be specifically pointed out in the appended claims, reference being had to the accompanying drawings exemplifying the invention, and in which—

Figure 1 is a side elevation of an improved clamping device constructed in accordance with the principles of this invention. Fig. 2 is a section on the line II—II, Fig. 1. Fig. 3 is a section similar to that shown in Fig. 2, showing the parts in loosened position to free the trolley line. Fig. 4 is a top plan view of the assembled clamping jaws detached from the suspension means. Fig. 5 is a longitudinal section of the clamping members through the axis of the pivotal connection therebetween. 55 Fig. 6 is an end elevation of the assembled

jaws in clamping position, the trolley line being shown in section. Fig. 7 is an inside elevation of one of the duplicate clamping members. Fig. 8 is a side elevation of the screw socket suspension. Fig. 9 is a detail section of the wedging collar. Fig. 9^a is a sectional view of the jaws in clamping position. Fig. 10 is a transverse section of another embodiment. Fig. 11 is a similar section, showing the parts in loosened position. Fig. 12 is a side elevation of the suspension device. Fig. 13 is a view similar to Fig. 6, showing a portion of the clamps gripping a trolley wire which is round in cross section.

70 Referring more specifically to the drawings and to the embodiment of the invention shown therein, an insulator 1 of well known construction is rigidly secured to a stationary part 2 by means of stud bolts 3 75 for which purpose the insulator 1 is provided with a base flange 4 through which the bolts 3 extend.

Projecting from a mass of insulation 5 within the insulator 1, is a pin or stud 6 80 threaded upon its outer end 7 to receive a threaded socket 8. Said threaded socket 8 is best shown in Fig. 8, and comprises an upper cylindrical body 9 and a lower circular head 10 separated from the body 9 by 85 a contracted neck portion 11. Within the outer wall of the cylindrical portion 9 is a slot or recess 12, within which a lug or spline 13 formed on the inner cylindrical wall of a wedging collar 14 engages. Said 90 wedging collar 14 is reciprocably mounted upon the cylindrical portion 9 of the screw threaded socket. The threaded stud 6 depending as it does from the support provided by the insulator 1 with the insulating material 5, together with the threaded socket 8, provides a suspension device for 95 the trolley clamp now to be described.

As shown best in Figs. 4, 5, and 7, the trolley clamp comprises a pair of movably 100 connected members 15 and 16, said members in the present embodiment being pivoted together preferably by making the members interchangeable and of the form shown in elevation in Fig. 7. Each of said members 105 comprises a clamping jaw 17 and a power arm 18 flared outwardly to provide a wedging surface 19. On one end of said member is provided a pin or trunnion 20 while on the other end is provided a socket 21 for the 110

reception of the pin 20 of the other clamping member. An inclined reinforcing rib 22 extends from the pin 20 to the wall of the socket 21 in the manner shown in Fig. 7 and adjacent one end is provided with an interlocking projection or lug 23, the lug 23 of each clamping member being adapted when the clamping members are assembled, that with a slight displacement will engage 10 with a lug or shoulder 24 of the other clamping member. The ribs being inclined will cross each other when the parts are assembled and will form the bottom of the recess in which the swivel head enters. Each 15 of the clamping members is provided with a recess or hollow 25 immediately above the strengthening rib 22. When the clamping members are assembled the recesses 25 register and are adapted to receive the head 10 of 20 the threaded socket 8. In order to provide means for supporting the clamping members from the head 10, an annular collar 26 is provided on each power arm to fit around the contracted portion 11 of the threaded 25 socket 8. It will be seen from the description that the collar 14 is reciprocably mounted upon the socket 8 and is provided below with a wedging surface 27 which slidably engages the wedging surface 19 of the power 30 arms of both clamping members.

For convenience in handling, the clamping members 15 and 16 are usually assembled about the head 10 of the threaded socket 8 with the collar 14 locked in position 35 on the socket 8, as shown best in Fig. 2. In order to maintain the parts in this assembled position, each of the lugs 23 may be displaced into the position shown in dotted 40 lines in Fig. 7, in which position it will interlock with the shoulder or lug 24 of the other clamping member. For this purpose the clamping members may be made of malleable metal.

Referring now to the embodiment shown 45 in Figs. 10, 11 and 12, the fixed support comprising the insulating shell 28, insulation 29 and threaded pin 30 embedded in said insulation is constructed exactly similar to that shown and described in the former 50 embodiment. The threaded socket 31 in this embodiment, however, is provided with an exterior thread 32 and a hexagonal flange 33 whereby it may be rotated upon the stud 30. The wedging collar 34 of this embodiment 55 is provided with internal threads engaging the threads 32 on the socket member 31. The wedging collar 34 is also provided with a hexagonal flange 35 whereby it may be rotated upon the threaded socket 31. By 60 means of this construction it will be evident that the threaded socket 31 having been screwed up against the insulator, the clamping members 15 and 16 may be moved into clamping engagement with the trolley line 65 36 by rotating the wedging collar 34 upon

the socket 31 and thereby causing the wedging surface 27' to force the outer arms 19 apart. When on the other hand it is desired to release the conductor 36, the wedging collar 34 may be moved in the opposite direction into the position shown in Fig. 11. 70

In Fig. 13 the extremities 15^a, 16^a, of the clamping members 15, 16, are of a slightly different shape so as to receive and grip a conductor 36^a which is round in cross section. Inasmuch as the wedging collar 14 is connected with the cylindrical portion 9 by means of the lugs or splines 13 projecting into the slots or recesses 12, a rotation of the collar will cause the threaded cylindrical 80 portion 9 to screw on to the threaded extremity 7 of the pin or stud 6. This movement will also adjust the clamping members 15, 16, with relation to the stud. This adjustment will cause portions of the clamping members 15, 16, to engage the wedging surface 27 and the upper surface of the collar 14 to abut the insulator 1, thereby arresting the adjustment of the collar 14 longitudinally with respect to the stud. A further rotation of the collar 14 will then cause the adjacent portions of the clamping members 15, 16, to move over the wedging surface 27 to effect a spreading action of the members 15, 16, thereby causing the latter 95 to grip the wire. 90

What is claimed as new is—

1. In a trolley wire clamp, the combination of a pair of complementary clamping members provided with registering recesses, 100 each of said members having a projection and a socket, the projection of one member entering the socket of the other member for connecting the members together for pivotal movement with respect to each other, there being a shoulder formed at the inner end of each projection and there being a projection formed on the inner face of each member adjacent the inner end of the respective sockets, said projections and shoulders being entirely housed between the clamping members, the projection on each member being adapted to be deflected behind the respective shoulder on the other member to lock the parts together, a support provided 105 with a swivel head engaging in said recess, and a wedge portion on said support adapted to project between portions of the clamping members to impart clamping action to said members. 110

2. In a trolley wire clamp, the combination of a pair of complementary members, each being shaped to form a lug at one end and a recess at the other end, the lug on one end of each of the members entering the 115 respective recess in the other member, the inner face of each member between the lug and recess being hollowed out to form a rib extending between the lug and recess and to form a shoulder at the inner end of the lug, 120 125 130

5 a portion of the rib of one member being deflectable behind the shoulder on the other member to lock the parts, said members being also provided with coöperating ears having portions coöperating with the ribs to form a recess, a swivel head engaging in the said recess, and a wedge portion on the head adapted to project between the said ears to impart a clamping action to the said

10 members.

15 3. In a trolley wire clamp, the combination of a pair of complementary members, each being shaped to form a lug at one end and a recess at the other end, the lug on one end of each of the members entering the respective recess in the other member, the inner face of each member between the lug and recess being hollowed out to form a rib extending between the lug and recess and to

20 form a shoulder at the inner end of the lug, said ribs being inclined so that when the

members are assembled the ribs will cross each other and form the bottom of the said recess, a portion of the rib of one member being deflectable behind the shoulder on the other member to lock the parts, said members being also provided with coöperating ears having portions coöperating with the ribs to form a recess, a swivel head engaging in the said recess, and a wedge portion on the head adapted to project between the said ears to impart a clamping action to the said members.

25 In testimony whereof I have signed my name to this specification, in the presence of 30 two subscribing witnesses, on this 30 day of November A. D. 1910.

CLETUS N. ALLERDING.
